PIN OPENER

Charles A. Cooper, South Jacksonville, Fla.

Application June 12, 1940, Serial No. 340,171

8 Claims. (Cl. 132—1)

This invention relates to a pin opener in combination with a tray. Although it is realized that this invention can be employed for opening various pins, such as cotter pins, snap pins and the like, it is especially useful for opening hair pins of the variety used by women and better known as "bobby pins."

An object of the invention is to present a simple inexpensive means for spreading ladies' hair pins, and means always being handy and ready for use.

Another object is to provide a pin opener in combination with a pin tray, and arranged in a manner that its convenience will always be taken advantage of because of its simplicity.

Other objects, advantages and features of my invention will appear from the accompanying drawing, the subjoined detailed description, the preamble of these specifications and the appended claims.

Applicant is about to illustrate and describe one of the forms of his invention in order to teach one how to make, use and bend the same, but it is to be understood that the drawing and description thereof are not to limit the invention in any sense whatsoever, except as limited by the appended claims.

In the drawing:

Fig. 1 shows one form of the invention in perspective view.

Fig. 2 is a cross section substantially along the line 2—2 of Fig. 1.

Fig. 3 shows a slightly modified form of the invention as it could be applied to Fig. 1, therefore, it is shown in cross section similar to Fig. 2.

Fig. 4 is a modified form of the invention shown in perspective view.

Fig. 5 is a cross section taken substantially along the line 5—5 of Fig. 4.

Fig. 6 is another modified form of the invention shown in perspective view.

Fig. 7 is a cross section taken substantially along the line 7—7 of Fig. 6.

In the preferred form of the invention shown in Figs. 1 and 2, it consists of a pin tray having a base plate 1 with integral upstanding walls 2 about the perimeter thereof. Across the middle portion of the tray is a partition 3 which is shown as integral with the base 1 along its bottom and the wall 2 at its ends. The tray may be molded from ceramic materials or be pressed or die casted from metals. It is immaterial just what materials may be used from which to form the tray, because the invention itself does not lie in the kind of materials used.

The partition 3 is configurated to aid in the opening of pins and especially those hair pins well known as "bobby pins." A typical "bobby" pin is shown at 4 having a rounded top and integral depending legs 5 and 6. These legs are generally wavy in form in order to firmly grasp the hair and stay in place upon a woman's head. The lower open end of the pin is shaped so as to readily receive hair; the lower end of one of the legs is bent outwardly at 4' away from the lower end of the other leg so as to make a flared opening. Such hair pins are made of metal having a good degree of elasticity so that the legs thereof will spring together when released from a spread condition.

Although the top of the partition 3 may have various shapes which would act as a wedge for spreading the legs of resilient hair pins, the top may be shaped as shown in Figs. 1, 2, 4, 5, 6 and 7. For such a wedging type of partition, the top 20 thereof is bevelled at 7 and 8 to provide a rather sharp ridge 9 therealong. The ridge of the partition need not necessarily be sharp to effectively act as a wedge for spreading pins, but since some hair pins do not have a very wide flared opening, 25 it is better to have the ridge sharp. The partition near its top at 10 should be wide to well spread the legs of the pins when they are forced downwardly thereon. The bevelled surfaces 7 and 8 should be roughened, as shown, by forming ridges in the material itself. Even the sides of the partition may be roughened by any suitable process. Instead of roughening the surfaces, rubber may be applied, especially when the material of the partition is copper or brass because 35 rubber can be readily vulcanized onto copper and brass. The roughened surface prevents the pin from slipping off the partition accidentally. A rubber pad 3' is shown as cemented or vulcanized to the tray depending upon whether the material of the tray is ceramic or metallic containing copper. "Bobby" pins can also be opened by pressing the end of their long leg onto a soft mat of rubber or any other soft material which would prevent the leg from slipping while the other leg 45 is pulled to open the pin. Therefore, the tray is provided with the rubber mat 3'.

In Fig. 3, it is shown how a partition 11 may be used instead of the partition 3. The partition has a wood chisel top which has a bevelled surface on just one side to form the sharp ridge 13. The bevelled surface of this partition is also roughened as shown.

Figs. 4 and 5 show a modified form of the invention in which the tray comprises a base 14 55

and spaced apart concentric walls 15 and 16. These upstanding walls are shown integral with the base. Intermediate the walls are a series of spaced apart partitions 17 forming a plurality of compartments 18. The tops of these partitions have bevelled sides 19 and 20 to form sharp ridges 21. Like the preferred form of the invention, the tops of the partitions 17 are wedge shaped and would also function to spread the legs of resilient hair pins. This form of the invention is provided with the rubber pad 14 cemented to the tray as shown.

Figs. 6 and 7 show still another form of the invention wherein the base 22 has an integral peripheral wall 23. The top of this wall has bevelled sides 24 to 26 which form a sharp ridge 26. Below the wedge top of the wall, the wall is reduced in size by the curved surfaces 27 and 28 as shown. This form of the invention also has 29 cemented to the bottom of the tray a rubber pad 22. The bottom 22 of the tray may be recessed to snugly receive the pad, or the bottom raised so that the top of the pad is on a plane with the top edge 20 of the wall.

Having thus described my invention, what is claimed as new and desired to be secured by Letters Patent is

1. In a hair pin opener, a tray, an upstanding wall extending across the tray and fixed thereto, said wall having a narrow ridge along its top and a relatively broad base.

2. The opener recited in claim 1 wherein the ridge of the wall is pyramidal in cross section.

3. A hair pin opener having a heavy tray shaped base and an upstanding wall thereon, said wall including a sharp edge, said wall having an upper part thereof roughened to prevent accidental slippage of the pin.

4. In a hair pin opener, a tray, an upstanding wall extending across the tray and fixed thereto, said wall having a narrow ridge along its top and a relatively broad base, said wall having an upper part thereof roughened to prevent accidental slippage of the pin.

5. A new combination including a tray and a resilient pad, said pad being fixed to the tray and adapted to receive the end of the long leg of a "bobby" pin and the like.

6. In a hair pin tray having a bottom and sides, resilient pad means fixed to the bottom of the tray and adapted to aid in the opening of pins having a short leg and a long leg pressed together by holding the long leg while the short leg is pulled away from it.

7. A new combination including a heavy pin tray and a wall fixed thereto with a sharp edge designed to spread hair pins.

8. In combination, a weighted pin tray and a hair pin opener, the pin opener comprising a wall having a sharp upper edge and a frictional portion in the tray.

CHARLES A. COOPER.
